US0D1004379S

(12) **United States Design Patent** (10) **Patent No.:** **US D1,004,379 S**
(45) **Date of Patent:** **** Nov. 14, 2023**

(54) **LEMON JUICE EXTRACTOR**

(71) **Applicant:** **Fuzhou Believe Industrial Co. Ltd.**,
Fuzhou (CN)

(72) **Inventor:** **Shiqing Chen**, Fuzhou (CN)

(73) **Assignee:** **Fuzhou Believe Industrial Co. Ltd.**

(**) **Term:** **15 Years**

(21) **Appl. No.:** **29/806,283**

(22) **Filed:** **Sep. 2, 2021**

(51) **LOC (14) Cl.** **07-04**
